US00D888846S

(12) **United States Design Patent** (10) Patent No.: **US D888,846 S**
(45) Date of Patent: **** Jun. 30, 2020**

(54) **EXERCISE APPARATUS**

(71) Applicant: **Kompan A/S**, Odense SØ (DK)

(72) Inventors: **Nikolaj Maj Bentsen**, Vejle Ø (DK);
Martin Nørgaard Johansen, Skårup
Fyn (DK)

(73) Assignee: **KOMPAN A/S**, Odense SØ (DK)

(**) Term: **15 Years**

(21) Appl. No.: **29/716,735**

(22) Filed: **Dec. 11, 2019**

Related U.S. Application Data

(60) Division of application No. 29/696,564, filed on Jun. 28, 2019, which is a division of application No. 29/631,256, filed on Dec. 28, 2017, now Pat. No. Des. 855,721, which is a continuation of application No. 35/500,802, filed on Mar. 1, 2016 (U.S. filing date under 35 U.S.C. 384), and having an international filing date of Mar. 1, 2016, now Pat. No. Des. 806,817.

CLAIM

The ornamental design for an exercise apparatus, as shown and described.

DESCRIPTION

FIG. 1 is a top, left perspective view of our new design for an exercise apparatus.

FIG. 2 is a left side elevation view of FIG. 1.

FIG. 3 is a back side elevation view of FIG. 1.

FIG. 4 is a right side elevation view of FIG. 1.

FIG. 5 is a front elevation view of FIG. 1.

FIG. 6 is a top plan view of FIG. 1; and,

FIG. 7 is a bottom plan view of Figure. 1.

The broken lines are included for the purpose of illustrating unclaimed subject matter and form no part of the claimed design.

1 Claim, 7 Drawing Sheets
